UNITED STATES PATENT OFFICE

JUSTIN R. SWIFT, OF EVANSTON, ILLINOIS, ASSIGNOR TO THE SUPERIOR TYPE COMPANY, OF CHICAGO, ILLINOIS, A CORPORATION OF ILLINOIS

MOLDING FLASK

Application filed July 1, 1927. Serial No. 202,925.

My invention relates to the art of molding, and particularly to apparatus adapted for use in producing molded rubber characters such as rubber stamps.

According to the known practice, a shallow flask is provided within which is placed a plastic composition in which impressions are made while still plastic, the material being thereafter permitted to harden and to act as a matrix for the subsequent production of one or more specimens of the object to be reproduced. In order to hasten the hardening or setting of the plastic material, it is and has been customary to place the flask and contained material in a dryer and apply heat thereto for a considerable period of time. In the use of the apparatus heretofore known, experience has shown that the drying time can not be shortened by increasing the degree of heat, for the reason that any substantial increase in the applied heat resulted in the formation of steam or other gases within the plastic material, the escape of which serves to disrupt the surface and to destroy the impressions theretofore made in the plastic material.

An object of my invention is to provide apparatus so constructed as to enable a much greater degree of heat to be applied in the drying operation and thereby to greatly reduce the drying time. The result is secured by providing in the floor of the flask a multiplicity of equally spaced apertures and combining with the flask a base plate having a multiplicity of equally spaced upwardly projecting pegs of substantially the size of the apertures in the floor of the flask. Preferably the base plate is of a size equal to that of the largest flask that will be employed. By reason of the arrangement of the pegs the base plate will, therefore, permit of the combination therewith of flasks of any size smaller than that of the largest size.

In operation, the flask is placed over the base plate, the pegs serving to close the openings in the floor of the flask. The flask is then filled with the plastic material and the impressions made in the material. Thereafter, the flask is lifted from the base plate, leaving the multiplicity of vent holes in the

floor. The flask and contained material is then placed in the drying oven and a high degree of heat applied thereto. The vent holes enable the escape of the gases from the material and prevent disruption of the walls of the mold. 55

The invention will be more readily understood by reference to the accompanying drawings, in which;

Fig. 1 is a plan view of a base plate and mold constructed in accordance with my invention; 60

Fig. 2 is a sectional view on the line 2—2 of Fig. 1, and

Fig. 3 is an enlarged sectional view with 65 the peg plate removed.

In the drawings, a support is indicated generally at 10 and on the support is mounted the plate 11 having a large number of equally spaced pegs, 12, projecting from the 70 upper face thereof.

A flask such as intended for use in connection with this apparatus is in the form of a shallow receptacle having a floor 13 provided with a multiplicity of apertures arranged in 75 the same spaced relation as the pegs, 12. The shallow molding space 15 within the flask is adapted to contain plastic material, indicated at 16 in Fig. 3, within which impressions are made while the material is still plastic. It 80 will be noted that the pegs 12 project entirely through the floor 13 of the flasks and into the cavity 15. As a result when the flask and peg plate are separated, a multitude of vent holes are provided through the floor of 85 the flask and extending into the plastic material in the form of small recesses or indentations. This permits the escape of steam or other gases that may be driven out by the action of heat on the plastic substance. According to the recommended practice, the peg plate 11 is constructed of a size as large as the 90 largest flask that will be employed. For example, in Fig. 1, a large flask is indicated by 95 the dotted lines 17, of such size that all of the pegs are utilized. This is also indicated in dotted lines in Fig. 2. A smaller flask 13 is also shown in position on the peg plate in the figures, the design of the flask being such that 100

whatever the length and breadth thereof, it may be positioned on the peg plate.

In the carrying out of the process, a flask such as indicated in the drawings is placed on the peg plate and the plastic material 16 placed in the flask. The impressions are then made in the plastic material and the flask removed from the peg plate. In the last step, the flask is placed in a dryer where it is subjected to a relatively high degree of heat. The first action of the heat is to form a crust over the top exterior surface before the interior has been relieved of its gases. However, the lower surface of the plastic material may still be permeated and the gases may easily escape through the vent holes formed by the withdrawal of the pegs from the opening. This is clearly shown in Fig. 3. After the plastic material has been dried and is hard, it is utilized as a matrix for casting rubber thereon, usually for the production of rubber type, rubber stamps, etc.

The number, size and distribution of the vent holes is a matter of importance and the essentials were determined only after long and careful experiment. In the construction illustrated, the openings are $\frac{1}{8}$ " diameter, arranged on $1\frac{1}{2}$ " centers. The pegs are of such length that their upper ends project $\frac{1}{2}$ " into the molding space. While these dimensions are not essential, they are recommended for successful practice.

Obviously modifications may be made in the construction shown, and I do not wish to be limited except as indicated in the appended claims.

I claim:

1. In combination, a base plate of a size equal to the size of the largest flask that is to be employed, said plate having a multiplicity of equally spaced vertical pegs in its upper surface, and a plurality of flasks of different sizes, each flask having a multiplicity of equally spaced holes in its floor, any one of said flasks being adapted to be accommodated on said base plate with the pegs filling said holes during the placing of the molding compound in the flask and the taking of the impressions in the compound and to be separated from the base plate before the compound is dried.

2. In apparatus for molding rubber type, the combination of a plurality of flasks of different sizes, each having in its floor a multiplicity of equally spaced through apertures, and a single base plate having a multiplicity of equally spaced vertical pegs, or pins, adapted to nicely fit into the apertures in any one of said flasks in order to fill said apertures until after the impressions have been made in the molding compound, the flask and plate being thereafter separated to permit the apertures to act as vents during a subsequent operation.

3. Molding apparatus of the class described, comprising in combination, a flask having a floor provided with a relatively large number of equally spaced through apertures, and a peg plate having a relatively large number of similarly spaced upwardly projecting pegs of an effective length slightly greater than the effective thickness of the flask floor, the flask and peg plate being adapted to be assembled during the placing of the molding material in the flask and the forming of the impressions in the material, and separated before the material is placed in a dryer.

In testimony whereof I have affixed my signature.
